SHOE SHINE CABINET

Filed Sept. 16, 1930 2 Sheets-Sheet 2

UNITED STATES PATENT OFFICE

LEO A. NOBLE, OF LONGMONT, COLORADO

SHOE SHINE CABINET

Application filed September 16, 1930. Serial No. 482,329.

This invention relates to a shoe shine cabinet adapted to be secured with respect to a wall, and has for its primary object to provide, in a manner as hereinafter set forth, 5 a cabinet of such class which presents an attractive appearance when closed, and the door of which is provided with a foot supporting pedestal which is brought into proper supporting position when the door is 10 opened.

A further object of the invention is to provide a cabinet of the character aforesaid in which the door is formed of sections 15 operatively connected together in such a manner that the sections will move simultaneously to open and close the door.

A further object of the invention is to provide a shoe shine cabinet in which the door is formed of sections which are provided 20 with coacting means whereby all of the sections will be held in closed position upon the latching of one of the sections in such position.

With the foregoing and other objects in 25 view, the invention consists of the novel construction, combination and arrangement of parts as hereinafter more particularly described, and as illustrated in the accompanying drawings wherein is shown an embodiment of the invention, but it is to be understood that the description and drawings are 30 to be taken as illustrative and that the invention is intended to be limited only by the scope of the claims hereunto appended.

In the accompanying drawings in which like numerals are employed to designate like parts throughout the several views:—

Figure 1 is a front elevation of a cabinet in accordance with this invention showing 40 the door thereof closed.

Figure 2 is a similar view showing the door open.

Figure 3 is a vertical section taken on the line 3—3 of Figure 1.

Figure 4 is a fragmentary rear elevation of the cabinet.

Figure 5 is a transverse section taken at a point indicated by the line 5—5 of Figure 3.

Figure 6 is a vertical section taken on the 50 line 6—6 of Figure 2.

Figure 7 is a top plan of the cabinet as shown in Figures 3 and 5.

Referring to the drawings in detail, the numeral 1 indicates an open front housing preferably formed at its forward face with 55 a flange 2 for abutment against the face of a wall, such as 3, with the housing 1 inset with respect to the face of the wall. The cabinet may be secured in position with respect to the wall in any suitable manner such as by means of suitable holdfast devices 4 extending through the flange 2 and into the wall.

The open front of the housing is provided with a door consisting of a central section 5 and a pair of side sections 6. Each of the sections 5 and 6 is secured to the flange 2 by means of a hinge 7. The section 5 is hinged to swing about a horizontal axis while the sections 6 are hinged to swing about vertical axes. The composite door is formed with a rearwardly curved, marginal portion 8 by means of which the central portion of the door is projected outwardly from the forward face of the flange 2.

Preferably formed integrally with the central section 5 are a pair of mutilated bevelled gears 9 which are vertically disposed and which mesh with a pair of horizontally disposed, mutilated bevelled gears 10, one of which is formed with or secured to each of the side sections 6. Adjacent the bottom of the door, the flange 2 is provided with a pair of angular recesses 11 through which portions of the gears 9 and 10 project. The gears 9 and 10 are constantly in mesh in order that the sections 5 and 6 will move simultaneously to open or closed position upon any movement of any one of the sections to open or close the same. The gears 9 are provided with offset lugs 12 which abut against the rear face of the flange 2 when the door is swung to open position in order to limit the opening movement of the door. Coincidentally with 95 the engagement of the lugs 12 with the rear face of the flange 2, the marginal portion 8 of the composite doors is brought into engagement with the forward face of the flange 2, whereby the marginal portion 8 also pro- 100

vides for limiting the opening movement of the door.

Secured to the inner face of the section 5, adjacent the upper end of the latter, is a foot supporting pedestal 13 which is automatically brought into proper foot supporting position upon the opening of the door. Upon the closing of the door, the heel portion 14 of the pedestal 13 is brought into engagement with a spring latch 15 carried by and projecting rearwardly within the housing 1. Upon the latching of the central section 5 in closed position by means of the engagement of the heel portion 14 of the pedestal 15 with the spring latch 15, the side sections 6 are latched in closed position by means of the meshing gears 9 and 10, and are further latched in closed position by means of projections 16 extending within corresponding recesses 17 formed at the upper corners of the central section 5. Disposed within the housing 1 are a pair of aligned shelves 18 which are spaced apart an appropriate distance to permit the insertion of the pedestal 13 therebetween when the door is swung to closed position. In spaced relation to the shelves 18, a shelf 19 is provided within the housing 1, the shelf 19 being provided centrally thereof with a slot 20 to make the space below more accessible, to prevent the use of this portion of the shelf for the storage of objects otherwise interfering with the closing of the pedestal into the housing when the door is swung to closed position. Adjacent the top thereof, the central section 5 is provided with a convenient handle member 22 which is pivotally connected with the outer face of the section 5.

It is to be noticed that the marginal portion 8, in conjunction with the meshed gears 9 and 10, provides positive means for limiting the opening movement of the door, and that the lugs 12 on the gears 9, in conjunction with the gears 10 meshing with the gears 9, also provide a means for positively limiting the opening movement of the door independently of the marginal portion 8. It is to be noticed further that the heel 14 of the pedestal and spring latch 15, in conjunction with the meshed gears 9 and 10, provide a positive means for maintaining the door closed, and that the heel 14 and spring latch 15, in conjunction with the projections 16 and recesses 17, also provide a means for pivotally maintaining the door closed independently of the meshing gears 9 and 10.

It is thought that the many advantages of a shoe shine cabinet in accordance with this invention will be readily apparent, and although the preferred embodiment of the invention is as illustrated and described, it is to be understood that changes in the size, shape and arrangement of parts may be resorted to, so long as such changes fall within

the scope of the invention as defined in the appended claims.

What I claim is:—

1. A shoe shine cabinet comprising, an open front housing, a sectional door for the open front of the housing, a foot supporting pedestal carried by one of the door sections, and meshing gear elements carried by the sections operatively connecting the latter together to provide for simultaneous movement of the door sections to opened and closed position upon such movement of one of the sections. 70 75

2. A shoe shine cabinet comprising, an open front housing, a sectional door for the open front of the housing, a foot supporting pedestal carried by one of the door sections, meshing gear elements carried by the sections operatively connecting the door sections together to provide for simultaneous movement of the door sections to opened and closed position upon such movement of one of the sections, and stop means carried by one of said gear elements for limiting the opening movement of the door sections to place the pedestal in proper foot supporting position when the door is open. 80 85 90

3. A shoe shine cabinet comprising, an open front housing, a sectional door for the open front of the housing, a foot supporting pedestal carried by one of the door sections, meshing gear elements carried by the sections operatively connecting the door sections together to provide for simultaneous movement of the door sections to opened and closed position upon such movement of one of the sections, and means for latching one of said sections in closed position. 95 100

4. A shoe shine cabinet comprising, an open front housing, a sectional door for the open front of the housing, a foot supporting pedestal carried by one of the door sections, means for limiting the opening movement of the pedestal carrying door section to place the pedestal in proper foot supporting position when the door is open, means for latching one of said sections in closed position, and meshing gear elements on the sections for maintaining the remaining sections closed upon the latching of one section and for causing simultaneous opening and closing movement of the sections upon such movement of one of the sections. 105 110 115

5. A shoe shine cabinet comprising, an open front housing, a sectional door for the open front of the housing, said sectional door including a centrally disposed section and a pair of side sections, a foot supporting pedestal carried by the central section, means operatively connecting the side sections with the central section to provide for simultaneous movement of the sections to opened and closed position, means for limiting the opening movement of the central section to place the pedestal in proper foot supporting posi- 120 125 130

tion when the central section is open, and means for latching the central section in closed position.

6. A shoe shining cabinet comprising, an open front housing, a sectional door for the open front of the housing, the sections of the door being hinged to the housing and having their free edges in opposed relation when closed, said free edges moving away from each other when opened, a foot supporting pedestal carried by one of the door sections, and means operatively connecting the door sections together to provide for simultaneous movement of all the door sections to opened and closed positions upon such movement of one of the sections.

In testimony whereof, I affix my signature hereto.

LEO A. NOBLE.
